UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

STITCHED BUTTONHOLE.

Application filed December 15, 1923. Serial No. 680,532.

To all whom it may concern:

Be it known that I, EDWARD B. ALLEN, a citizen of the United States, residing at Newtown, in the county of Fairfield and State of Connecticut, have invented certain new and useful Improvements in Stitched Buttonholes, of which the following is a specification, reference being had therein to the accompanying drawings.

This invention relates to stitched buttonholes and has for an object to provide a fabric with a buttonhole, the threads of which are so arranged and concatenated as to give the buttonhole unusual body and strength independently of the character of the fabric, and hence adapt it for knitted fabrics of loose texture. Another object of the invention is to improve and strengthen the bar of buttonholes of the type in which the final stitches overlie the initial stitches beyond and in line with one end of the buttonholeslitz and generally known as fly-barred buttonholes. Such buttonholes are customarily provided with one or more reinforcing cords over which the stitches are laid, and a further object of the invention is to more securely anchor the cord or cords at the barred end of the buttonhole so that the buttonhole will strongly resist stresses tending to stretch or distort it.

To the attainment of the ends in view the invention comprises a fabric in which is stitched an overseam having on one face a plurality of upper threads disposed side by side in zigzag fashion and formed at intervals into loops which pass through to the other face of the buttonhole where they are keyed by loops of a pair of under threads, each loop of under thread passing through a plurality of loops of upper thread and being entered by a subsequently formed plurality of loops of upper thread. The portions of the two under threads which connect the under thread loops lie along the inner and outer margins of the overseam and the under thread loops pass alternately in opposite directions across the under face of the overseam. Where one or more cords are used, as in overseaming a buttonhole, they are preferably laid centrally of the overseam along the bottom, or bottom and top, surfaces of the body-fabric and are bound down by the loops of under thread and the zigzag upper thread portions connecting the upper thread loops. The invention is not to be

understood, however, as limited to the use of a cord or cords or to the laying of a cord or cords between the intermediate rows of loops of the zigzag threads as it may in some cases be deemed preferable to omit all cords or to use a cord of such thickness or so lay the cord that it will be penetrated by loops of one or both of such rows, particularly at the barred end of a buttonhole where secure anchorage of the ends of the cord is desirable.

In the accompanying drawings, Fig. 1 is a view of the under or "right" side of a stitched buttonhole embodying the invention. Fig. 2 is a view of the upper side of the buttonhole. Figs. 3 and 4 are under and upper face views of the overseam as used to join the abutted edges of cut fabrics. Figs. 5 to 11, inclusive, are a series of views illustrating the formation of the present overseam.

In the preferred embodiment of the invention, as illustrated, 1 represents a body-fabric on the upper face of which, Fig. 2, a pair of upper threads 2, 3 are disposed in zigzag fashion. The zone *a* of one zigzag upper thread is displaced outwardly from but preferably overlaps, i. e., is not spaced entirely to one side of, the zone *b* of the other zigzag upper thread; the zones *a* and *b* being non-coincident. The thread 2 is formed alternately at the points 4, 5 and the thread 3 alternately at points 6, 7 into the respective loops 4', 5', 6' and 7' which pass through to the under face of the fabric where they appear in four rows and are keyed by loops of a pair of under threads 8, 9.

As will be observed in Fig. 1, the thread 8 is formed into loops 10 which pass through upper thread loops 4', 6' and are entered by upper thread loops 5', 7', which latter are entered by loops 11 of the other under thread keyed in turn by being entered by upper thread loops 4', 6'. The portions of the under threads 8, 9 which connect the respective loops 10, 11, lie along the margins of the overseamed zone *d*.

A bottom cord 12 and top cord 13 may be incorporated in the buttonhole by laying them along the respective faces of the body-fabric and forming the stitches over them.

The particular embodiment of the invention illustrated in Figs. 1 and 2 is a buttonhole of the eyelet-end fly-barred type where-

in the final stitches are superposed upon the initial stitches in line with and beyond one end of the buttonhole-slit 14. Such a buttonhole may conveniently be made by the 5 machine of my copending application Serial No. 680,833, filed herewith and comprising a pair of reciprocating and laterally jogging needles 15, 16, carrying, respectively, the upper threads 2, 3, and a pair of alternately 10 acting loopers 17, 18, carrying, respectively, the under threads 8, 9, and operating in conjunction with the loop-detainers 19, 20.

Referring to Fig. 5, the needles 15, 16, have penetrated the fabric 1 and are passing 15 their respective loops through the loop 11 of under thread 9 held spread by the detainer 20. The detainer withdraws and as the needles rise, Fig. 6, their loops 4', 6', are seized by the looper 17 which projects 20 a loop 10 of under thread, Fig. 7, through the upper thread loops 4', 6'.

The loop detainer 19 advances and seizes 25 the loop 10 of under thread after which the looper 17 withdraws, leaving its loop on the detainer 19, Fig. 8, which latter holds the loop 10 in position for entry by the needles 15, 16, on their next descent, Fig. 9.

As soon as the loop 10 is entered by the 30 needles, the detainer 19 is withdrawn to shed such loop. As the needles rise, Fig. 10, they throw out loops 5', 7', which are seized by the looper 18 carrying the under thread 9, a loop 11 of which thread is thereby passed through the upper thread loops 5', 7', 35 Fig. 11. The loop 11 is next seized by the detainer 20 and presented to the needles 15, 16, as shown in Fig. 5. This completes a cycle of operations. In sewing a corded 40 fly-bar button-hole embodying the invention, some of the multiplicity of closely spaced upper thread loops, resulting from the use of two zigzag upper threads, usually penetrate the cord at the barred end of the buttonhole and thereby anchor the cord all 45 the more securely.

It has been proposed to increase the body 50 and strength of a buttonhole in knit goods by sewing a plurality of times around the hole, but this expedient is time consuming and the finished buttonhole is unattractive. According to the present invention a 55 shapely buttonhole of unusual body and strength is produced by an overseam passing once only around the buttonhole.

The present overseam, on a somewhat 60 larger scale, may be used for joining the abutted edges of cut knit goods, as shown in Figs. 3 and 4, wherein *x*, *y*, represent 65 separate pieces of knit goods having their cut edges abutted at the line *z* substantially centrally of the overseam. In this form of the invention the loops 4', 7', of the two outer rows of upper thread loops are anchored deeply in the pieces *x*, *y*, and resist 70 strains tending to separate such pieces, while

the loops 5', 6', of the two inner rows are formed relatively near to the abutted cut edges of the pieces *x*, *y*, and bind down the loops 10, 11 of under thread which cross the line of division *z* and tie together the deeply 75 anchored loops 4', 7'. The inner rows of loops 5', 6', in conjunction with the loops 10, 11, securely bind down the cut threads of the pieces *x*, *y*, along the line of division *z* so that such cut threads will not stick up 80 objectionably. It will be noted that the present overseam is not a duplex seam, i. e., not made up of two separate and distinct 85 seams sewed one over the other and is not divisible into simpler component seams 90 each complete in itself, but constitutes one integral concatenated thread-loop structure.

Having thus set forth the nature of the invention, what I claim herein is:—

1. A stitched buttonhole comprising a 95 fabric having an overseam including upper thread means formed into four laterally spaced rows of loops passing through to the under face of the fabric, and a pair of under threads extending along the margins of the overseam and formed into loops each of which passes through a loop of upper thread in each of the two adjacent rows and embraces a loop of upper thread in each of the two remote rows.

2. A stitched buttonhole comprising a 100 fabric having an overseam including a pair of upper zigzag threads disposed in overlapping zones and formed into four rows of loops passing through to the under face of the fabric, and a pair of under threads extending along the margins of the overseam and formed into loops each of which passes through a loop of upper thread in each of the two adjacent rows and embraces a loop 105 of upper thread in each of the two remote rows.

3. A stitched buttonhole comprising a 110 fabric having an overseam formed with a plurality of upper threads disposed in zig-zag arrangement in non-coincident zones and having loops passing through the fabric, and under thread means formed into keying loops each of which passes through loops of a plurality of upper threads.

4. A stitched buttonhole comprising a 115 fabric having an overseam formed with a plurality of upper threads disposed in zig-zag arrangement in non-coincident zones and having loops passing through the fabric, and under thread means formed into keying loops which are concatenated with the loops of the upper threads, each loop of under thread passing through a loop of each upper thread and embracing a succeeding 120 loop of each upper thread.

5. A stitched buttonhole comprising a 125 fabric having an overseam formed with a plurality of upper threads disposed in zig-zag arrangement in non-coincident zones 130

and having loops passing through the fabric, and a pair of under threads formed into loops which are concatenated with the loops of the upper threads, each loop of each under thread passing through a loop of each upper thread and embracing a succeeding loop of each upper thread.

6. A stitched buttonhole comprising a fabric having an overseam formed with a plurality of upper threads disposed in zig-zag arrangement in overlapping zones and having loops passing through and keyed at the under face of the fabric, and a top cord disposed in the overlapping portion of said zones and bound down by said upper threads.

7. A stitched buttonhole comprising a fabric having an overseam formed with a plurality of upper threads disposed in zig-zag arrangement in overlapping zones and having loops passing through the fabric, a pair of under threads formed into loops which are concatenated with the loops of up-

per threads, and a bottom cord bound down by said under thread loops, one cord end 25 and the final stitches of the overseam overlapping the other cord end and the initial stitches to form a fly-bar at one end of the buttonhole.

8. A stitched buttonhole comprising a 30 loosely knitted fabric having an overseam formed with a plurality of upper threads disposed in zigzag arrangement in non-co-incident zones and having loops passing through the fabric, and a pair of under 35 threads formed into loops which are concatenated with the loops of the upper threads, each loop of each under thread passing through a loop of each upper thread and embracing a succeeding loop of each 40 upper thread, the final stitches of the overseam overlapping the initial stitches at one end of the buttonhole to form a fly-bar.

In testimony whereof, I have signed my name to this specification.

EDWARD B. ALLEN.
